UNITED STATES PATENT OFFICE.

GEORGE F. MORGAN, OF NEW YORK, N. Y.

AXLE.

1,399,069.

Specification of Letters Patent.

Patented Dec. 6, 1921.

Application filed April 15, 1921. Serial No. 461,492.

To all whom it may concern:

Be it known that I, GEORGE F. MORGAN, a citizen of the United States, residing in New York city, in the county of New York 5 and State of New York, have invented certain new and useful Improvements in Axles, of which the following is a specification.

The invention relates to axles and more particularly to axles for railway cars and 10 the like.

When a railway car or similar vehicle running upon fixed rails turns a curve, the wheel on the outer track of the curve travels through a greater distance than the wheel 15 on the inner track. This causes a difference in velocity in the travel of the two wheels in rounding the curve, and particularly if it is a sharp one, which necessarily results in much grinding and wear of both the rails 20 and of the wheels by reason of the slipping of one or both of the wheels. Much expense for repair is thus occasioned and not infrequently for accidents. It has accordingly been proposed to provide some means for 25 obviating this long recognized difficulty. One proposed means is to provide a car axle with one fixed and one loose wheel thereon. Such axles, however, as heretofore constructed have been either more or less complicated, 30 and, consequently, unsatisfactory in operation; or they have lacked proper provision for lubrication and preventing dust and grit from entering the bearings. The stresses to which a railway car axle is subjected in 35 rounding a curve are relatively severe, and it is accordingly necessary that the construction be strong and simple.

The object of the present invention is to produce an improved axle adapted for use 40 on railway cars and other vehicles traveling on fixed rails. The invention consists in the novel manner of mounting the loose wheel upon the axle so as to secure efficiency in operation and relatively long usage without impairment of the efficiency and without 45 the necessity of repairs. A feature of the invention resides in the means whereby provision is made for lubrication. The invention itself consists in the improved axle 50 described in the following specification and particularly pointed out in the appended claim.

In the accompanying drawing is illustrated the preferred form of the invention. 55 The figure is a sectional side elevation. The

improved railway car axle as illustrated in the drawing comprises an axle proper 1 which is provided at its opposite ends with the usual journal bearings 2 and 3. At one end of the axle is mounted the loose wheel 4 and at the other end of the axle is mounted the fixed wheel 5, which is not mounted in position until after the loose wheel is in place. The successful operation of a railway car axle provided with a loose wheel mounted thereon requires that provision be made for the greatest possible strength and durability the nature of the construction will permit.

The lateral or axial thrust upon the loose 70 wheel is as great as the lateral or axial thrust upon the fixed wheel, and thus it is necessary to provide the loose wheel with thrust surfaces so arranged that there will be no liability of lateral or axial movement 75 of the loose wheel. Moreover, it is desirable that the loose wheel be provided with relatively large bearing surfaces so as to prevent an undue wear. It is necessary also that simple and efficient means be provided for 80 securing a proper lubrication of the loose wheel. These features of construction are provided in the manner of mounting the loose wheel in the present invention.

A more extended bearing surface is secured by mounting the loose wheel 4 on collars fixed on the axle 1, than by mounting the loose wheel directly on the axle; and by elongating the hub 6 of the loose wheel. On the outer end of the axle adjacent the journal bearing 3 is affixed a collar 7. It will be noted that the length of the collar 7 is such that it extends from the journal bearing 3 to a point coincident with the plane of the inner edge of the flange 8 of the loose 90 wheel. This construction insures a maximum of bearing surface (consistent with the mechanics of the construction) at that part where the greatest wear necessarily falls. In assembling the axle with its wheels 100 the collar 7 is first pressed or shrunk on the axle and then the loose wheel is mounted thereon from the other end of the axle. The loose wheel is slipped on the collar 7 as far as the inner edge 9 of the internal and annular flange or web 10 formed on the hub 6. A second collar 11 is then pressed on the axle until its inner end meets the outer edge 12 of the flange 10. Thus the loose 105 wheel is effectively held against lateral or 110

axial movement. In order that the collar 11 may be removed in case it is necessary to rebore the loose wheel 4 and in order that the collar 11 under this condition may have an effective grip upon the axle, the axle is slightly tapered at this point, as is clearly shown in the drawing. The inner end 13 of the hub finds a bearing surface on the outer end 14 of the collar 11 and thus the loose wheel is further steadied on its bearing and is prevented from wobbling, even when the main bearing surface is considerably worn.

Lubrication is effected from the journal box 15, the inner surfaces of the hub 6 of the loose wheel being provided with the usual lubricating grooves so that the oil or other lubricant may find free passage from the journal box 15 to the end of the hub 6. To prevent dust and grit from entering the bearings at the inner end of the hub, the head of the collar 11 is provided with a flange 16, which embraces a space filled with packing 17. A packing 18 of resilient material is interposed between the outer end of the hub 6 and the inner end of the journal box 15 to prevent dust and grit from entering the bearing from this end and also prevent the lubricant from passing out. The outer end of the hub is recessed at 19 and the inner end of the journal box is recessed at 20 to provide for effectively holding the packing 18 in place and render it

more efficient in the performance of its function.

35

By reason of the simplicity of construction of the improved railway car axle described above the axle is adapted to withstand the stresses to which it is subjected. The novel form of thrust surfaces for holding the loose wheel against lateral or axial movement conduces to this simplicity of construction and consequent strength and efficiency in operation. This simplicity of construction lends itself to the novel means 40 for lubricating the loose wheel and preventing dust and grit from entering the bearings.

Having thus described the invention what I claim as new is:—

50

An axle for railway cars and the like having journal bearings and comprising a wheel fixed at one end of the axle, a collar fixed at the opposite end of the axle, a loosely mounted wheel journaled on the collar, the inner end of the collar being substantially coincident with the flange of the wheel, a second collar fixed on the axle and spaced apart from the first collar and affording bearing for an elongation of the hub of the 55 loosely mounted wheel, and a flange on the hub engaged by the collars to prevent longitudinal movement of the loosely mounted wheel.
